YARN-TRAVERSING DEVICE

John Pringle Mackie, Belfast, Northern Ireland,
assignor to James Mackie & Sons Limited, Belfast,
Northern Ireland, a British company

Application February 16, 1943, Serial No. 476,102
In Great Britain February 20, 1942

2 Claims. (Cl. 242—43)

This invention relates to machines for winding yarn. Various suggestions have been made for effecting the traverse of the yarn by rollers with double helical grooves in their surfaces and with particular means for guiding the yarn at the crossing points of the helices. It has also been suggested to feed the yarn from a guide offset to one side or end of the grooved roller and to use a single helical groove for traversing the yarn from that side toward the other, relying on the lateral pull from the offset guide to effect the return of the yarn to the starting point. In one British specification dealing with a proposal of this type, No. 529,150, a helical series of disconnected notches or recesses was provided in the roller between the turns of the continuous helix for assisting in the control of the return of the yarn under the pull from the offset guide.

According to the present invention the yarn is guided from a position near the centre toward either end of the traverse by a grooved roller with oppositely directed helices on its two end portions, which helices may overlap a little at the centre but do not cross one another. The traverse of the yarn toward the two ends is effected by the two helical grooves, while the return toward the mid-position is effected by the lateral pull of the yarn from the yarn guide, and this suffices to bring back the yarn to the point at which the helical groove for transferring it to the opposite end of the roll begins.

The invention is illustrated in the accompanying drawing, wherein—

Figure 1 is a plan view showing diagrammatically the arrangement of the winder for winding a cylindrical roll or cheese of yarn;

Figure 2 is a development of the surface of the grooved roller shown in Figure 1;

Figure 3 is a similar view to Figure 1 illustrating the winding of a cop.

Referring first to Figure 1, the yarn is led from a supply source to a yarn guide 6, and past a fixed finger or abutment 7 to the surface of the winding roller 8 which runs in contact with the roll of yarn 9 being wound. The surface of the roller 8 is formed with two oppositely directed helices 10 and 11 each extending from near the centre toward one end of the roller, but so that they do not cross one another. The groove 10 terminates in a broadened end 12 near the centre of the roller, and the groove 11 has a similar broadened end 13 which overlaps the end 12 to some extent. The other ends of the grooves

terminate in short return tracks 14 and 15 which are just sufficient to start the return traverse of the yarn from each end.

It will be seen that the guide eye 6 is displaced a little toward the left, say $\frac{1}{8}$ of an inch from the centre line, while the finger or abutment 7 is similarly displaced but to a less extent, say $\frac{1}{4}$ inch from the centre line. The effect of the finger 7 is to impart a pull to the yarn at the start of the reversal at the left hand end, equivalent to that of a guide eye displaced toward the right from the centre line, while when the direction of winding of the yarn is being reversed from the right hand end the pull is direct from the guide eye 6 as indicated by dotted lines in Figure 1. The finger 7 thus serves to equalise the rate of traverse of the yarn, making the angle of the yarn from the end of the roller 8 at the start of the reverse winding approximately the same as if the guide eye 6 were offset toward the opposite side. The end 13 of groove 11 extends past the centre line toward the same side as that to which the guide eye 6 is offset, while the end 12 of groove 10 extends substantially up to the centre line but not beyond it in this case.

As the yarn is wound it is carried out say toward the left hand end by engagement in groove 10 until it is reversed at the end 14. Then the pull of the yarn from the guide eye 6 and round the finger 7 serves to cause the return traverse of the yarn toward the centre line, but just before the centre line is reached the yarn catches in the broad end 13 of groove 11 and is carried out toward the right hand end of the roller. At this end the reverse bend 15 in the groove 11 starts the return traverse of the yarn, and the direct pull of the yarn from the guide eye 6 completes the traverse toward the centre. This pull suffices to bring the yarn back far enough to cause it to drop into the broad end 12 of the groove 10 and so the traverse repeats itself as the roll 9 is wound. The finger 7 is about $2\frac{1}{2}$ to 3 inches nearer the roller 8 than the guide eye 6 in the example shown but considerable variation is possible in the relative positions of the guide eye 6, finger 7 and roller 8 while attaining the desired result.

In the example shown the roll of yarn 9 is driven by contact with the grooved roller 8 but it may of course be separately driven. The same form of grooved roller 8 may be used for winding yarn on the tapered ends of cops and the like, as indicated for example in Figure 3, in which it is assumed that the cop 16 is separately driven.

In the gaps between the helices 10 and 11 one or more disconnected notches may be provided like those of British patent specification No. 529,150 if desired to assist in the return traverse of the yarn, but this is not found to be necessary in practice.

If the ends of the helical grooves 10 and 11 can be arranged to overlap sufficiently at the middle of the roller a centrally disposed guide eye 6 can be used, but it is generally easier to secure the desired result if one of the grooves extends a little past the centre of the roller as illustrated, and if the guide eye 6 is displaced a little toward that side of the traverse path as above described. The depths of the grooves may vary toward the ends, particularly toward the inner end of each where it is broadened to assist in picking up the yarn for traversing it toward the outer end of its path.

I claim:

1. A yarn traversing device for winding machines comprising a roller having two oppositely disposed helical grooves in its surface extending from about the middle of the roller toward opposite ends thereof, the adjacent inner ends of said grooves being widened and disposed to overlap on one side of the centre of the roller but

without intersection, in combination with a yarn guide offset a short distance from a plane through the centre of the roller toward that side at which said groove ends overlap one another, and additional yarn guiding means adapted to make more acute the angle between the line of travel of the yarn and the surface of said roller while the yarn is being traversed over the portion only of said roller embraced by one of said helical grooves.

2. A yarn traversing device for winding machines comprising a roller having two oppositely disposed helical grooves in its surface extending from about the middle of the roller toward opposite ends thereof, the adjacent inner ends of said grooves being disposed to overlap on one side of the centre of the roller but with intersection, in combination with a yarn guide offset a short distance from a plane through the centre of the roller toward that side at which said groove ends overlap one another, and an abutment between said yarn guide and the roller adapted to deflect the path of the yarn from the yarn guide toward one end of the roller while not affecting the path of the yarn toward the other end of said roller.

JOHN PRINGLE MACKIE.
